JOIST STRUCTURE

Adolf H. Schaffert, Youngstown, Ohio, assignor
to Truscon Steel Company, Youngstown, Ohio,
a corporation of Michigan

Application April 20, 1931, Serial No. 531,525

4 Claims. (Cl. 189—37)

This invention relates to a metal beam of the type having a nailing strip as a part thereof.

A serious objection to previously used devices of this type has been the development of squeaks in the floor supported by such joists, after the floor has been laid. These squeaks are very objectionable, and it is usually necessary that the floor be taken up in order to eliminate them after they have developed. This often involves great

10 expense.

A series of experiments and investigations have shown that these squeaks are usually caused by the shrinking of the nailing strip in the channel member of the rafter, which shrinkage causes 15 the nailing strip to become slightly loose and movable in the channel member. The slight movement of the floor, which this looseness allows when a weight passes over it, causes the squeak, and it may occur between the floor and sub floor, 20 the sub floor and nailing strip, or the nailing strip and rafter member.

Attempts have been made to overcome this difficulty by kiln-drying the nailing strip and painting it before insertion into the channel member 25 of the joist, the object being to preserve an even moisture content which will prevent shrinkage. This method has, however, proved unsatisfactory. At the place of utilization, the joists are often left 30 in the open and it has been found that the nailing strips absorb a certain amount of moisture in spite of the coating of paint. Likewise under the conditions of a heated building or in any manufacturing plant where the floor is subjected to heat, moisture will be driven off with a consequent shrinkage.

The object of the present invention is to provide such a joist structure in which the nailing strip is more permanently secured against movement with relation to the rafter regardless of the 40 amount of shrinkage.

A further object is to provide such joist structure in which the nailing strip is substantially waterproof and is thus not subject to expansion and shrinking due to absorption and elimination 45 of moisture.

Another object is to provide an advantageous structure of the above type which will not materially increase the expense of manufacturing it.

50 In the accompanying drawings:

Figure 1 is a perspective view of the joist.

Figure 2 is a sectional view on lines 2—2 of Figure 1.

55 Figures 3 and 4 are cross sectional views showing two stages in the assembling of the joist.

Figure 5 is a cross sectional view of the completed joist.

Figure 6 is a perspective view of a modification.

Figure 7 is a sectional view on the line 7—7 of Figure 6.

Figure 8 is a view similar to Figure 7 of another modification.

Figure 9 is a perspective view of the modified top chord member shown in Figure 8.

In the preferred embodiment shown in Figures 1—5 an upper chord member 1 is supported by a lower chord member 2, and an intermediate lattice member 3. The upper chord member 1 is channel-shaped having a bottom portion 4 and upstanding side walls 5 between which a nailing strip 6 is engaged. The upper chord member 1 is preferably rolled from plate steel.

At spaced intervals in the side walls 5 are inset portions 7. As shown in Figure 2 these inset portions are alternately disposed on the two side walls.

The inset portions 7 are formed at the time of forming the member 1, the addition of one set of rolls to the machine used for that purpose being sufficient to form them.

Figure 3 shows in cross section a chord member 1 as it is completed by the rolling mill, welded to the lattice 3 and ready to receive the nailing strip. After the upper chord member is welded to the lattice member, as shown in Figure 3, a nailing strip 6 is positioned between the side walls 5 thereof and resting on the bottom portion 4, as shown in Figure 4. The side walls 5 of the upper chord member are then pressed towards each other, preferably by means of rollers, into close engagement with nailing strip 6 lying between them. The result of this operation is that the inset portions 7 are embedded in the nailing strip 6, as shown in Figures 2 and 5. The inset portions 7 hold the nailing strip 6 against all movement, and any shrinkage of the nailing strip will rather cause it to contract more tightly against the inset portions, thus more securely holding the parts against relative play as the shrinkage progresses. This being for the reason that shrinkage or contraction of the material of the nailing strip which lies interiorly adjacent the embedded projections causes the upper and lower walls of the pocket or channel in which the projection lies to

approach each other, thus bearing more tightly against the corresponding edges of the projection. More broadly, the shrinkage of the entire strip causes its top edge to approach its bottom edge. Any two points on the surface or in the

body of the strip, are caused to approach each other by the shrinkage of the material between them. Thus upon shrinkage of the material which lies between the planes of the walls of the 5 pocket in which the projection lies, the walls approach each other and clamp the projection more tightly between them.

As it is, however, advisable to prevent changes in the moisture content of the nailing strip, it is 10 made substantially waterproof. This is preferably accomplished by saturating the strip with a mixture by volume made up of the following ingredients:

	Per cent
15 Linseed oil	40
Spar varnish	20
Dryer	10
Naptha	28
Paraffin	2

20 It has been found that if the nailing strips are dried to a moisture content of approximately 8% and immersed in the above mixture for a period of one-half hour, the mixture will penetrate practically all the way through the nailing strip, 25 and after such treatment there will be no appreciable swelling from absorbing moisture. After waterproofing the nailing strips they are placed in the upper chord members as above described.

30 In the modification shown in Figures 6 and 7, the inset portions 7 are replaced by inturned lip or flange portions 7a, which are formed and embedded in the nailing strip in substantially the same manner as in the embodiment first described. In this form longitudinally extending channels 8 are preferably cut in the sides of the nailing strip to receive the lip portions 7a. This is done to prevent the danger of splitting of the nailing strip which might occur if the lip portions 40 were simply forced into the nailing strip as are the insets in the other form.

In the modification shown in Figures 7 and 8, spaced portions of the side walls are bent inwardly to form lip or flange members 7b. The members 45 7b are alternately disposed on the side walls so that those borne by one side wall are not opposite those borne by the other side wall. This form of chord member is also formed by rolling, after which the waterproofed strip is inserted be-

50

tween the walls, and the walls are then rolled towards each other into close engagement with the nailing strip, embedding the lip portions 7b in the adjacent sides of the nailing strip.

80 From the foregoing, it is thought that the construction, operation and many advantages of the herein described invention will be apparent to those skilled in the art without further description, and it will be understood that various changes in the size, shape, proportion and minor details of construction may be resorted to without departing from the spirit or sacrificing any of the advantages of the invention.

85 What I claim, is:

1. A joist structure including an upper chord member having upstanding side walls, and a substantially water proof nailing strip positioned between the side walls, portions of the side walls being embedded in the sides of the nailing strip and gripped by the material thereof upon contraction of the said nailing strip.

90 2. A joist structure comprising a channeled chord member, and a nailing strip engaged in the channel of the chord member and immovably carried by the chord member and portions of the chord member being embedded in the nailing strip for holding the latter against play irrespective of the expansion and contraction of the nailing strip, and being more tightly gripped by the nailing strip when it contracts.

95 3. A joist structure comprising a channeled chord member having upstanding side walls, a nailing strip positioned between and engaged by the side walls and extending above the side walls, portions of the side walls being embedded in the 100 sides of the nailing strip at points substantially below the top surface of the nailing strip and enclosed above and below by the material of the nailing strip and tightly gripped thereby when the nailing strip contracts.

105 4. A joist structure comprising a channeled chord member having upstanding side walls, a nailing strip positioned between and engaged by the side walls, spaced portions of each of the side walls being inset and embedded in the sides of 120 the nailing strip and enclosed and engaged above and below by the material of the nailing strip, the said portions being tightly engaged by the said material upon contraction of the nailing strip.
